UNITED STATES PATENT OFFICE

163,469

STRAP FASTENER AND HOOK

Allen M. Moody, New Albany, Ind.

Application December 15, 1949, Serial No. 6,643

Term of patent 3½ years

(Cl. D17—12)

To all whom it may concern:

Be it known that I, Allen M. Moody, a citizen of the United States of America, residing at New Albany, in the county of Floyd and State of Indiana, have invented a new, original, and ornamental Design for a Strap Fastener and Hook, of which the following is a specification, reference being had to the accompanying drawings, forming part thereof.

Fig. 1 is a perspective view of the strap fastener and hook showing my new design;

I claim:

The ornamental design for a strap fastener and hook, as shown.

ALLEN M. MOODY.
